UNITED STATES PATENT OFFICE.

WILLIAM F. SCHMIDT, OF WYANDOTTE, MICHIGAN, ASSIGNOR TO ALL METAL PRODUCTS COMPANY, OF WYANDOTTE, MICHIGAN, A CORPORATION OF DELAWARE.

PISTOL.

Application filed April 16, 1925. Serial No. 23,578.

To all whom it may concern:

Be it known that I, WILLIAM F. SCHMIDT, a citizen of the United States, residing at Wyandotte, county of Wayne, State of Michigan, have invented a certain new and useful Improvement in Pistols, and declare the following to be a full, clear, and exact description of the same, such as will enable others skilled in the art to which it pertains 10 to make and use the same, reference being had to the accompanying drawings, which form a part of this specification.

My invention relates to pistols and an object of my improvements is to provide a simplified and improved retracting and releasing mechanism, and one especially adapted to toy pistols.

I accomplish this purpose in the device illustrated in the accompanying drawings, in 20 which—

Figure 1, is a sectional elevation of an apparatus embodying my invention.

Figure 2, is a partial view similar to Figure 1 showing the mechanism in a different 25 position.

Figure 3, is a section on the line III—III of Figure 1.

Figure 4, is a perspective view of the retracting lever.

Figure 5, is a perspective view of the trigger piece.

a, is the stock forming a casing for the actuating mechanism. This casing is made of sheet metal in two corresponding halves 35 that are placed together in the usual way to form the stock. The part of the casing toward the observer is removed in Figures 1 and 2.

c, is the barrel; *d*, is a piston adapted to 40 reciprocate in the barrel *c*. *e*, is a compression spring adapted to throw the piston *d* forward to compress the air and actuate the projectile. *g*, is the retracting rod, the forward end of which is secured at the center of the piston *d* and which extends through the coil spring *e* and into the cavity toward the rear of the stock. *g*², is a slot formed through the rear end of the rod *d*.

h, is the trigger piece pivoted upon a pin 45 *h*² bearing in the stock or casing *a* and provided with a lug *h*³ which engages back of the spring *e* so that said spring acts to return the trigger piece to its normal position.

j, is a retracting lever provided with an 50 arm *j*² which extends upward through the

slot *g*² and is bent over, as shown at *j*³, Figure 4, to prevent the arm *j*² from coming out of the slot *g*². The lever *j* is provided with an arcuate slot *j*⁴ and through this slot passes the pivot pin *k* which bears in the two walls of the casing or stock *a*. The lever *j* extends in a projection *j*⁵ toward the trigger piece *h* and this projection is turned up at its lower edge in a portion *j*⁶ which is then again turned to form a guiding and 60 engaging portion *j*⁷. The retracting lever *j* is made of sheet metal and lies against one of the interior surfaces *a*², (Fig. 3) and the part *j*⁶ engages and is adapted to slide along the other interior wall, of the casing *a*. The left hand edge of the projection *j*⁵ is turned upward at right angles to form the lug *j*⁷. 65

The trigger piece *h* is made of sheet metal which extends and is adapted to reciprocate 70 in a slot through the handle of the stock *a*; the projection *h*⁴ extending into said stock and being turned upward along its outer edges to form the flange *h*⁵.

m, *m*², are two branches of a light spring 75 which extends in a coil around the shank of the pin *k*, its branch *m* engaging against the forward edge of the part *j*⁶ of the retracting lever and the branch *m*² engaging against the rear wall of the casing *a*. This spring is 80 always under tension and normally acts to force the retracting lever *j* forward so that the rear end of the slot *j*⁴ engages the shank of the screw *k*, as shown in Figure 1.

The operation of the above described device is as follows:

Normally, the parts are in the position shown in Figure 1 where the piston *d* is thrust forward carrying the arm *j*³ of the retracting lever *j* forward and holding said 90 lever in engagement with the rear wall of the slot *g*² and the shank of the pin *k* in engagement with the rear wall of the slot *j*⁴. In this position, the projection *h*⁴ from the trigger piece *h* engages under the part 100 *j*⁵ of the retracting lever *j*.

When the trigger *h* is drawn backward, the projection *h*⁴ acts against the part *j*⁵ of the retracting lever *j* to rotate said lever about the pin *k*, drawing the rod *g* backward by means of the arm *j*³ and when the trigger has been drawn far enough, the end of the projection *h*⁴ passes the outer end of the projection *j*⁵ from the lever *j* releasing said lever, which is then rotated back 110

to its first position by the action of the spring *e* on the arm *j*³.

When the trigger piece *h* is released, it is rotated by the spring *e* about the pivot pin 5 *h*² back towards its normal position, the projection *h*⁴ engaging against the flange or lug *j*⁷, as shown in Figure 2, forcing the retracting lever *j* backward, as shown in the last named figure so that the pin *k* is 10 brought into the forward part of the slot *j*⁴, and the projection *h*⁴ is permitted thereby to slide past the end of the projection *j*⁸ so that the trigger may return to its normal position. The spring *m* acting against the 15 retracting lever *j* now forces said lever back to the position shown in Figure 1 where it is ready to be again actuated as above described.

The flange *h*⁷ forms a broad wearing surface 20 upon the retracting lever *j* and the flange *h*⁵ forms a broad wearing surface on the projection *h*⁴. The part *j*⁶ of the retracting lever engages so as to easily slide forward and backward upon the inner surfaces *a*³ of the casing *a* and coacts with the part of said retracting lever engaging the surface *a*² of the casing *a* so as to form a convenient and durable guiding means for the retracting lever.

30 What I claim is:—

1. In an apparatus of the kind described, the combination of a lever, a trigger piece adapted to actuate said lever, said lever being provided with a slot, a pivot pin for 35 said lever extending through said slot, the said lever and trigger piece being relatively so arranged that the trigger piece shall actuate said lever and pass by the same in its motion in one direction and shall contact 40 said lever and force it out of the way to allow the return of said trigger piece on its motion in the other direction, said movements being permitted by the relative movement of the pin in said slot.
- 45 2. In an apparatus of the kind described, the combination of a lever, a trigger piece adapted to actuate said lever, said lever being provided with a slot, a pivot pin for said lever extending through said slot, the 50 said lever and trigger piece being relatively so arranged that the trigger piece shall ac-

tuate said lever and pass by the same in its motion in one direction and shall contact said lever and force it out of the way to allow the return of said trigger piece on its 55 motion in the other direction, said movements being permitted by the relative movement of the pin in said slot, and a spring acting to move and yieldingly hold said lever in its first named position.

3. In an apparatus of the kind described, a retracting rod, a pivoted lever engaging said rod so as to retract the same on turning in one direction, a slot in said lever, a pivot pin passing through said slot, a trigger piece adapted to rotate said lever to retract said rod in one position of said lever relative to said pin and to pass by said lever to return to its initial position when said lever is located at another position relative to said pivot pin, means for positioning and yieldingly holding said lever so that said pin shall be located in said slot to form a pivot for said lever when first acted on by said trigger piece, said trigger piece being adapted to pass by said lever at the end of its retracting motion and on its return movement to force said lever to a position at which said pin is located in said slot so that the trigger piece may return to 80 its normal position past said lever.

4. In an apparatus of the kind described, the combination of a sheet metal retracting lever and a trigger piece, said lever and trigger piece having pointed projections extending toward each other, the point of the trigger piece being adapted to engage said lever on both sides of said point, the metal of said lever being turned up to form flanges on both sides of said point joining 90 at the point.

5. In an apparatus of the kind described, a lever formed of sheet metal in combination with a casing, said lever being adapted to engage one wall of said casing and slide 95 thereon, said lever being turned upward at its edge and then over to form a surface adapted to engage the other wall of said casing.

In testimony whereof, I sign this specification.

WILLIAM F. SCHMIDT.
